UNITED STATES PATENT OFFICE.

HENRY F. NELSON, OF ANGOLA, LOUISIANA, ASSIGNOR OF ONE-HALF TO JOHN R. SANDERS, OF ANGOLA, LOUISIANA, AND ONE-HALF TO MAURICE R. WOULFE, OF WASHINGTON, DISTRICT OF COLUMBIA.

COMBINATION-LOCK.

1,111,487.

Specification of Letters Patent. Patented Sept. 22, 1914.

Application filed November 25, 1913. Serial No. 803,015.

To all whom it may concern:

Be it known that I, HENRY F. NELSON, a citizen of the United States, residing at Angola, in the parish of West Feliciana and State of Louisiana, have invented a new and useful Combination-Lock, of which the following is a specification.

The present invention appertains to a permutation or combination lock, and aims 10 to provide a novel and improved device of that character which shall be particularly applicable to trunks, suit cases, and the like, although it may be employed in various other capacities to advantage.

15 The present invention contemplates a novel assemblage of coöperable parts, in order that the desired results may be carried out in an efficacious manner, and in order that the structure will be comparatively 20 simple, compact and inexpensive, as well as enhancing the utility of the device.

With the foregoing general objects outlined, and with other objects in view which will be apparent as the nature of the invention 25 is better understood, the present invention resides in the combination and arrangement of parts and in the details of construction hereinafter described and claimed, it being understood that changes 30 in the precise embodiment of the invention herein disclosed can be made within the scope of what is claimed without departing from the spirit of the invention.

The invention has been illustrated in its 35 preferred embodiment in the accompanying drawing, wherein:—

Figure 1 is a front view of the lock as applied to a trunk, suit case or the like. Fig. 2 is a sectional view taken on the line 40 2—2 of Fig. 1. Fig. 3 is an inside or interior view of the lock, the back or case being removed and portions being broken away. Fig. 4 is a horizontal or longitudinal section of the lock, taken on the line 45 4—4 of Fig. 1.

In the drawing, the numeral 1 designates the body of a trunk, suit case or the like, having the cover or closure 2, it being understood that the said parts may be taken as 50 typical, so as to represent various structures to which the present lock is applicable.

In carrying out the present invention, the body 1 is provided with a recess or opening 3 adjoining the cover 2, and preferably of

rectangular outline with its longest dimension disposed parallel with the edge of the body.

The present lock embodies a face plate 4, which has its body portion inset or sunk as 5 at 5, to fit snugly within the recess or opening 3, the marginal or rim portions of the base plate being secured to the outer side or face of the body 1 around the opening 3. Thus the central or main portion of the face 60 is inset from the face of the body 1 and provides a recess for the reception of certain 65 of the parts, as will hereinafter more fully appear.

The present invention also employs a hasp 6 hinged or pivoted to the cover 2 and which 70 has its free end portion offset, as at 7, to engage within the depressed or recessed portion 5 of the face plate, as clearly seen in Fig. 2. The offset or free end portion 7 of the hasp is provided with a loop-shaped 75 keeper 8 insertible through an opening or slot 9 provided in the face plate, that is, when the hasp is swung to closed position 80 against the face plate.

Means are provided on the back or inner 85 side of the face plate for locking the hasp, and to this end, a latch bolt 10 is guided for longitudinal sliding movement upon the back of the face plate, by means of a suitable guide 11, one end of the latch bolt 10 being adapted to be shot or projected through 90 the keeper 8 when the keeper is inserted through the opening or slot 9 of the face plate.

As a means for actuating the latch bolt 90 10 a handle or knob 12 is disposed within the recessed or sunken portion of the face plate to be accessible from the exterior, and is provided with a spindle or pintle 13 journaled through the face plate below the latch 95 bolt 10. A finger 14 is secured to the inner end of the spindle or pintle 13 and its free end engages a talon or notch 15 formed in the bottom of the latch bolt 10 intermediate its ends. It is evident that by rocking or 100 oscillating the handle or knob 12, the latch bolt may be shot or projected into engagement with the keeper 8, and may also be retracted or withdrawn out of engagement with the keeper.

The permutation means embodies a plurality of tumbler disks 16, 16', and 16'' disposed upon the inner side of the face plate

in co-axial or concentric relation adjoining the tail end of the latch bolt, the tumbler disks 16, 16' and 16'' having the respective nested or concentric shafts 17, 17' and 17'' journaled through the face plate, and bearing the respective dials 18, 18' and 18'' at their outer extremities. The tumbler disks are preferably adjustable rotatably upon the shafts, in order to permit the companion 10 tumbler disks and dials to be adjusted angularly with respect to one another for varying the combination, as will be obvious. The shaft 17'' connecting the tubular disk 16'' and the dial 18'' which engage the face 15 plate, is tubular and is journaled through the face plate, the shaft 17' connecting the tumbler disk 16' and the dial 18' which bear against the disk 16'' and the dial 18'' respectively, is tubular and is journaled 20 through the shaft 17''; and the shaft 17 connecting the remote or outermost tumbler disk 16 and dial 18 is preferably solid and is journaled through the intermediate shaft 17'. The tumbler disks are preferably of 25 uniform or like diameter, while the dials 18, 18' and 18'' are of graduated diameters, in order that the graduated peripheries of the dials will be exposed to view, and for purpose of manipulating the dials. The dials 30 coöperate with the suitable pointer upon the face plate in order that the dials may be properly set, to bring the gate notches 19 of the tumbler disks into registration for receiving the tail of the latch bolt and to permit 35 the latch bolt to be thrown open to release the keeper 8. The movement of the finger 14 is preferably limited by means of a lug 20 upon the inner side of the face plate, to prevent the latch bolt from being 40 excessively shot through the keeper 8, and to prevent the finger from swinging out of engagement with the latch bolt, or talon thereof.

The interior parts carried by the back of 45 the face plate, are preferably inclosed by means of a back plate or case 21, which is detachable, from the interior, in order that the tumbler disks may be adjusted for altering the combination of the lock. 50 In use, after the cover 2 has been closed, the hasp 6 may be readily swung so that the offset portion 7 swings within and engages the shoulder formed by the depressed or sunken portion of the face plate, which, 55 primarily, locks the cover in position, and at the same time, the keeper 8 in passing through the slot 9, also serves to lock the cover in position. It is to be understood, that to permit the keeper 8 to be inserted 60 through the slot 9, the latch bolt must have

been previously retracted, the tail of the latch bolt entering the registering gate notches 19 of the disk tumblers. To lock the hasp in position, it is merely necessary to swing or partly turn the handle or knob 65 12, to shoot the latch bolt through the keeper 8, and then by displacing the dials with respect to one another, the combination will be destroyed, so that the latch bolt cannot be retracted by unwarranted or malicious 70 persons, not possessing the requisite combination.

Attention is directed to the fact that when the lock is in use, the offset portion 7 of the hasp, the handle or knob 12 for actuating 75 the latch bolt, and the dials 18, 18' and 18'', will be housed or completely received by the sunken or depressed portion of the face plate, to prevent the said parts from being battered or otherwise injured in the transportation of the trunk or the like to which the lock is applied.

To open the trunk, the respective dials are properly set with respect to the pointer, which is facilitated by the indices on the 85 dials, so that the gate notches 19 will be brought into register, adjoining the tail of the latch bolt, and consequently, the latch bolt may be retracted out of engagement with the keeper 8, so that the hasp may be 90 thrown open for permitting the cover or closure to be swung open.

From the foregoing, taken in connection with the drawing, the advantages and capabilities of the present device will be manifest to those versed in the art, and need not be further commented upon. 95

Having thus described the invention, what is claimed as new is:—

A lock embodying a face plate having a 100 sunken portion forming a shoulder and provided with an opening, a hasp having its free end portion offset to swing within the said sunken portion of the face plate and to engage the said shoulder, a keeper carried by the offset portion of the hasp insertible through the said opening, means carried by the inner side of the face plate engageable with the keeper, and means disposed within the sunken portion of the face 105 plate and coöperable with the aforesaid means for actuating the same.

In testimony that I claim the foregoing as my own, I have hereto affixed my signature in the presence of two witnesses.

HENRY F. NELSON.
